UNITED STATES PATENT OFFICE.

DANIEL BELL, OF CHICAGO, ILLINOIS, ASSIGNOR TO INVINCIBLE LAUNDRY EQUIPMENT CO., A CORPORATION OF ILLINOIS.

CLOTHES DRIER.

Application filed April 4, 1927. Serial No. 180,650.

This invention relates to a clothes drier of the rotary type and concerns itself more particularly with the interior structure of the drying cylinder which is adapted for retaining a plurality of clothes holding units in which the clothes are kept separate during the rotation of the cylinders.

The invention comprises the novel structure and combinations of parts hereinafter described and more particularly pointed out and defined in the appended claims.

In the accompanying drawings which illustrate a preferred embodiment of this invention and in which similar reference numerals refer to similar features in the different views:

Figure 1 is a top plan view of a drying machine involving this invention.

Figure 2 is a sectional view taken upon the line II—II of Figure 1.

Figure 3 is an enlarged sectional view taken upon the line III—III of Figure 1.

Figure 4 is an enlarged fragmentary sectional view taken upon the line IV—IV of Figure 1, showing parts in elevation.

Figure 5 is a front elevational view of the drying machine.

Figure 6 is a fragmentary sectional view taken upon the line VI—VI of Figure 2, with the exhaust fan shown in elevation.

Figure 7 is a perspective view of one of the clothes holding units.

Figure 8 is an enlarged sectional view taken upon the line VIII—VIII of Figure 3.

Figure 9 is a fragmentary elevational view looking from the left hand side of Figure 1.

Figure 10 is a fragmentary rear elevational view showing the damper regulation for the air exit passage.

As shown on the drawings:

As an exemplification of this invention, there is shown a casing 1 having a lower rectangular portion provided with a heating chamber between the members 2 as shown in Figure 2. Suitable steam heating pipes 3 or the like are located in the heating chamber for supplying the heating medium. The lower rectangular portion of the casing merges into an upper cylindrical portion 1^a in which the rotary drying element is supported. With reference to Figure 3 it will

be noted that there is a closure plate 4 just above the heating chamber for causing most of the hot air to circulate around the left hand side of the drying element as shown by the arrow.

The drying element consists of a plurality of compartments 5 for removably receiving the clothes holding units 6 shown in perspective view in Figure 7. Each clothes holding unit is in the form of a drawer or box-like structure provided with a perforated bottom 7 and an open top. The compartments are formed by circular end plates 8 (Figures 2 and 3) which are connected and maintained in spaced relation by the connecting plates 9 which are provided with terminal flanges 9^a secured to the end plates. The top of each compartment is formed by a perforated plate 10 provided with terminal flanges 11 secured to the side plates 8. These plates 10 are provided with non-perforate right angled portions 12 which connect with a plate 9 whereby a hollow interior cruciform like structure is provided through which the hot air is not adapted to pass, thereby causing the hot air to circulate around the central closed cruciform chamber, and through the drying units which surround such chamber. The top plate 10 of each compartment is provided with a latch 13 which snaps down over the front end of each unit for retaining the same in its compartment. These drawers 6 are slidably supported upon suitable angle members 14 which are secured to the end plates 8 as shown more clearly in Figure 8.

The end plates 8 are centrally provided with bearings 15 (Figures 2 and 4) which are attached thereto. The rear end bearing 15 has affixed thereto a trunnion 16 which is journalled in a bearing 17 supported on an angle member 18 projecting from the rear of the casing. The front bearing 15 has fixed therein an operating shaft 19 which is journalled in a suitable bearing 20 supported on an angle 21 extending from the front end of the casing. A worm gear 22 is loosely mounted upon the outer ends of the shaft 19. This worm gear 22 is provided with a hub adapted for forming one member of a jaw clutch. The other member 23 of the jaw clutch is slidingly splined

upon the shaft 19. This movable clutch member 23 is provided with the usual groove for receiving the yoke 24 of a shipper lever 25 (Figure 1) which is pivoted at an intermediate point as indicated at 26. The end of the shipper lever 25 is provided with an upright end 27 which is shown more clearly in Figure 9 and which extends adjacent a switch box S that controls the motor. This upright end has a laterally extending stop arm 28 which is adapted to extend across the path 29 of the switch lever 30 which starts and stops the motor. The arm 28 is adapted to be either below or above the switch lever 30 so that the motor cannot be started or cannot be stopped until the clutch lever 27 has been actuated for disengaging the clutch from the worm gear 22. Consequently the motor cannot be accidentally started if something should strike or come in contact with the switch lever when working around the machine during the loading or unloading thereof.

The motor is indicated at 31. It is supported on a platform 32 extending from the front end of the casing. The motor is provided with an elongated shaft 33 which is provided with a worm 34 that meshes with the worm gear 22. Beyond the worm 34 there is a jaw clutch member 35 upon the motor shaft which is adapted for engagement by a jaw clutch 36 on a hand crank 37 which is rotatably mounted upon the end of the shaft. When the machine has been stopped and it is desired to remove the clothes holding units, the operator may manually rotate the drying element through the instrumentality of the crank 37 for bringing the compartments into alignment with a door 38 on the casing so that the unit 3 may be removed or inserted with respect to their compartments.

As before related, the hot air will pass up through the perforated tops and bottoms of the drying units 6 and thoroughly dry the clothes therein during the revolution of the drying element. The hot air escapes through a passage 39 which is formed by the outer wall of the casing 1 and an inner wall 40 which consists of a plate member having terminal flanges 41 attached to the rear end of the casing. The aforementioned passage 39 communicates with a pipe 42 (Figures 2 and 6) which leads to a fan 43 which is driven by a motor 44 and which is controlled by a switch box S'. The motor 44 is supported upon a suitable platform 46, the fan 43 and platform 46 being supported upon a frame 47 adjacent the front face 60 of the casing as shown in Figure 2. The fan 43 is illustrated as of the rotary type having an upper exhaust passage 48.

The amount of hot air passing through the drying chamber may be regulated by a damper 49 (Figure 3) in the passage 39.

The damper is secured to a suitable rod which extends through the casing and is provided with a handle 50 which is shown more clearly in Figure 10. This handle is provided with a suitable locking detent for engaging depressions 51 in the rear wall of the casing. Obviously the adjustment of the handle 50 will regulate the damper to control the amount of air passing through the drying chamber.

With reference to Figure 5 it will be noted that the lower front portion of the heating chamber is provided with a perforated section 52 for the admission of air to the heating chamber.

During the operation of this machine it will be obvious that due to the plate 4 and the imperforate cruciform interior of the rotary clothes unit holder, most of the hot air is compelled to pass around the left hand portion of the drying chamber as viewed in Figure 3. It cannot take a short cut to the suction passage 39 and thus evade certain clothes units. It will also be appreciated that the clothes are securely confined in each compartment, making it impossible for clothes in different compartments to become mixed. Each drawer or unit is adapted to contain the clothes of one customer. It is therefore necessary that the clothes in each drawer be kept separate from those in another drawer. It should be further noted that the door 38 of the casing is located so that the drawers will be in horizontal position, with their open tops directly upwardly when the same are removed or inserted with respect to their compartments.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a clothes drying machine, a rotary member having a central closed chamber, and compartments around said closed chamber, and individual clothes holding units removably confined in said compartments.

2. In a drying machine, a rotary member having a plurality of compartments closed at their inner ends and perforated at their outer ends, and material holding units in said compartments.

3. In a drying machine, a rotary member having a plurality of compartments closed at their inner ends and perforated at their outer ends, means in connection with said closed inner ends for providing a central closed chamber and a container removably retained in each compartment.

4. In a drying machine, a rotary member having means providing a closed interior central chamber, a plurality of compart-

ments around said closed interior and containers removably mounted in said compartments.

5. In a drying machine, a rotary member having means providing a closed central chamber, spaced compartments around said closed chamber, each compartment comprising lower guide members and a perforated

top, and a container having a perforated bottom removably supported upon said guide ¹⁰ members.

In testimony whereof I have hereunto subscribed my name at Chicago, Cook County, Illinois.

DANIEL BELL.
